Office Action dated Feb. 2, 2018, issued in counterpart Japanese Application No. 2017-011618.

Primary Examiner — Patricia A Palasik(74) *Attorney, Agent, or Firm* — Westerman, Hattori, Daniels & Adrian, LLP**CLAIM**

The ornamental design for an end plate for motion guide device, as shown and described.

DESCRIPTION

FIG. 1 is a front elevational view of a second embodiment of an end plate for motion guide device, showing our new design.

FIG. 2 is a rear elevational view thereof.

FIG. 3 is a right side elevational view thereof.

FIG. 4 is a left side elevational view thereof.

FIG. 5 is a top plan view thereof.

FIG. 6 is a bottom plan view thereof.

FIG. 7 is a perspective view, showing the front, top, and right-side thereof.

FIG. 8 is a perspective view, showing the rear, bottom, and left-side thereof.

FIG. 9 is a perspective view, showing the front, bottom, and right-side thereof; and,

FIG. 10 is a perspective view, showing the rear, top, and left-side thereof.

The broken lines illustrate environmental structure and form no part of the claimed design. The dot-dash lines form boundaries of the claimed design and form no part thereof.
